UNITED STATES PATENT OFFICE.

WILLIAM BUCKRIDGE NUTTING, OF PORTLAND, OREGON.

SPARK ARRESTER.

1,416,968.

Specification of Letters Patent. Patented May 23, 1922.

Application filed November 3, 1921. Serial No. 512,556.

To all whom it may concern:

Be it known that I, WILLIAM B. NUTTING, a citizen of the United States, residing at Portland, in the county of Multnomah and 5 State of Oregon, have invented certain new and useful Improvements in Spark Arresters; and I do declare the following to be a full, clear, and exact description of the invention, such as will enable others skilled in 10 the art to which it appertains to make and use the same.

This invention relates to an improved spark arrester which is especially designed for attachment to the top of smoke stacks 15 on factories and the like, being also adaptable for use on the stacks of locomotives or the like.

The principal object of the invention is to generally improve upon devices of this 20 class by providing one of extreme simplicity and durability which is applicable to stacks without requiring any alterations of the latter, the device being such in construction that effectiveness of operation is insured and 25 free escape of the smoke and gases permitted while dangerous sparks and hot particles are prevented from escaping and are returned into the stack.

Another and very important object of the 30 invention is to provide a spark arrester which embodies superposed cones, the lower one of which is considerably larger and is inverted and the upper one being reversed so that the spark and hot cinders will strike its 35 inner surface and be deflected laterally and downward and back into the stack.

A further and important object of the invention is to provide an arrester embodying the aforesaid construction together with 40 guide means for the sparks and cinders arranged inside of the lower cone and disposed over the upper end of the attaching pipe to effectively direct the sparks against the inner face of the upper cone, together 45 with a novel deflecting device which has the additional function of decidedly increasing the life of the upper cone by preventing the hot sparks from concentrating in the apex of the latter and damaging the metal.

50 Other objects and advantages of the invention will be apparent during the course of the following description.

In the accompanying drawing forming a 55 part of this specification and in which like numerals are employed to designate like parts, the figure represents a perspective view of an arrester constructed in accordance

with this invention, portions of the parts of the latter being broken away to disclose the construction and arrangement more clearly. 60

Before proceeding with the detailed description of the invention, I wish to state that the device may embody an attaching pipe to be telescopically engaged with the upper end of the stack on which the device 65 is to be mounted or the lower one of the superposed cones may be directly connected to the stack. However, by considering the following description, it will be seen that the first named construction is preferred. 70

Referring to the drawing in detail and wherein the preferred embodiment of the invention is clearly illustrated, it will be seen that the numeral 1 designates a section of pipe of suitable length which is designed 75 to be telescopically engaged with the upper end of a smoke-stack. Supported on and secured to the upper end of this attaching pipe 1 in any suitable way are superposed cones 2 and 3 respectively, the first named 80 of which is considerably larger and is inverted while the remaining one is smaller and is reversed. The upper edge of the lower cone is turned inwardly to provide a continuous flange 4 which serves to assist in 85 preventing escape of sparks and cinders. The lower end of the remaining cone is formed with an inturned flange 5 which is positioned below the first named flange and is spaced from the inner wall of the inverted 90 cone to provide a space through which the smoke and gases are permitted to escape. Suitable brackets 6 are employed for connecting the cones together in the position 95 shown and in proper spaced relation to permit free escape of the smoke and gas. Attention may here be directed to the fact that the upper end of the attaching pipe extends slightly into the interior of the lower cone 2 as indicated at 7 and a pocket 8 is thus 100 formed between this pipe and inner wall of the last named cone which serves to collect a small portion of the particles. Openings 9 are formed at the base of this cone and serve to permit escape of the particles from 105 this pocket.

Supported beneath the apex of the cone 3 and spaced from the inner face of this cone by means of suitable brackets 10 is an inverted conical deflector 11 which serves to 110 direct sparks against the inner face of this cone 3 so that they will then be deflected laterally and downward against the inner face of the cone 2 and will either drop into the

aforesaid pocket 8 or fall back into the smoke-stack. Of course, all of the particles will not take this course and because of the strong draft created in the stack, some of the finer particles will be carried outwardly with the smoke and will float into the atmosphere. In actual practice, this conical reflector 11 will be made of heavier metal than the other parts and thus prevented from being destroyed by the intense heat and hot sparks which contact it. By deflecting the hot particles in the manner above suggested, the greater portion of them is prevented from becoming concentrated in the apex of the upper cone and the life of the latter is thereby greatly lengthened. For the purpose of assuring effectiveness of operation, I also make use of a comparatively wide ring 12 which acts as a guide and serves to direct the hot particles into contact with either of the cones 11 or 3. Suitable brackets 14 serve to support the ring directly over the pipe 1. It may be added here that the ring 12 is considerably greater in diameter than the attaching pipe and that the diameter of the upper end of the inverted deflector cone 11 is just slightly larger in diameter than the attaching pipe 1.

In operation, the hot sparks and cinders are directed upwardly through the stack and into the arrester under the influence of the draught created in the stack and as they enter the arrester through the pipe 1, they are guided into contact with the downwardly inclined face of the conical deflector 11 and are partially broken up into fine particles. Some of the latter move into contact with the inner face of the cone 3 and are deflected downwardly against the corresponding face of the cone 2 while others are directed laterally and downward as soon as they contact the deflector cone. Some of the particles are then deposited into the pocket 8 and permitted to escape through the openings 9 while others are dropped back into the smoke-stack. Of course, some of the particles find a way between the cone 11 and cone 3 and collect in the first named cone. From practical experience, however, it has been found that practically all of the particles deposited in the inverted cone will in time burn up and leave only fine ashes which are forced out of this cone in some instances by the draught or by the newly deposited heavier particles.

By carefully considering the description in connection with the drawing, persons familiar with devices of this class will doubtless be able to obtain a clear understanding of the invention. Therefore, a more lengthy and detailed description is deemed unnecessary.

Since probably the best results may be obtained with the construction and arrangement herein shown and described, this is

taken as the preferred embodiment of the invention. However, I wish it to be understood that minor changes coming within the scope of the invention as claimed may be resorted to if desired.

70

I claim:

1. A spark arrester including superposed cones, the upper one of which is comparatively larger and has its apex disposed upwardly and the lower one of which is considerably smaller and has its apex disposed downwardly with its base portion arranged within the corresponding portion of the first named cone and with its apex extending below the base of said first named cone, the base portion of said inverted cone being spaced from the inner face of the large cone, whereby the smaller cone is permitted to act as a deflector and as means for preventing direct contact of the hot particles with the upper and apex portion of the large cone.

75

2. A spark arrester comprising superposed cones, the lower one of which is considerably larger and inverted and the upper one of which is arranged with its apex disposed upwardly, the base of said last named cone being arranged inside of the corresponding part of the lower cone and being spaced from the inner face of the latter to provide a space for escape of smoke and gases, an attaching pipe connected with said lower cone, a guide ring supported by the latter and disposed directly over said attaching pipe, and an inverted conical deflector supported from said upper cone and disposed in vertical alignment with said ring and attaching pipe for deflecting hot sparks and cinders laterally against one or the other of said first named cones.

90

3. A spark arrester comprising superposed cones, the lower one of which is truncated and is considerably larger than the upper one, and is inverted, and the upper cone having its apex arranged upwardly, the base portion of said last named cone being arranged inside of the corresponding part of the lower cone and being spaced from the inner face of the latter to provide a space for escape of the smoke and the gases, an attaching pipe connected with the lower reduced end of the lower cone and extending into the interior thereof, a guide ring of greater diameter than the pipe positioned inside of the lower cone and disposed directly over the pipe, being spaced away from the inner face of the lower cone, and a conical deflector supported from the intermediate portion of the upper cone, having its base spaced from the inner face of said last named cone and having its apex extending below the lower edge of the latter into the upper portion of said guide ring.

100

In testimony whereof I have hereunto set my hand.

WILLIAM BUCKRIDGE NUTTING.
